UNITED STATES PATENT OFFICE.

WILLIAM WILKIE, OF GLASGOW, SCOTLAND.

APPARATUS FOR OPENING AND PRESSING THE SEAMS OF WEARING-APPAREL.

1,249,267.

Specification of Letters Patent.

Patented Dec. 4, 1917.

Application filed March 1, 1917. Serial No. 151,743.

To all whom it may concern:

Be it known that I, WILLIAM WILKIE, a British subject, residing at Glasgow, Scotland, have invented certain new and useful

5 Improvements in Apparatus for Opening and Pressing the Seams of Wearing-Apparel, of which the following is a specification.

The present invention relates to machines 10 for opening and pressing the seams of wearing apparel, and it is especially applicable to open and press the seams of trousers and of sleeves of coats and jackets during manufacture. The invention resides in and comprehends the provision of certain improvements, 15 hereinafter described at length, in or relating to the construction and mounting of the movable pressing member which cooperates with a fixed pressing member or 20 support, as usual, and which is designed to be raised or lowered at will, after having been positioned, to be forced toward the fixed pressing member in order to impose the desired pressure upon the work. The invention 25 more particularly resides in the devices utilized for applying this downward pressure upon the movable pressing member and in the actuating means associated with such devices, and it also resides in the provision 30 of an improved seam-opening device which is carried by the movable pressing member and is adapted to penetrate the seam as the garment is moved over the stationary or work-receiving member.

35 The invention also resides in the provision, as a whole, of a machine of the above-described type which may be readily and quickly operated and which at the same time shall be extremely simple in its construction 40 while possessing a high degree of efficiency.

The invention will be fully described with reference to the accompanying drawings.

Figure 1. is a side elevation of the machine.

45 Fig. 2. is a front elevation of the same.

Fig. 3. is a perspective detached view of the arms in the operation of opening and pressing the seams drawn to an enlarged scale.

50 Fig. 4. is a front view of part of a machine for treating curved seams.

Upon an iron frame A a horizontal arm B is mounted fixed to the frame at one end and supported at the other end by movable 55 block C, the purpose of the movable block being to allow of trousers, sleeves or other

garments or parts of garments being slipped on to the arm B, and when in position supporting the free end of the arm B when weight or pressure is applied to it. Above 60 the fixed arm B another similar arm D is suspended on balance weighted levers E capable of being lowered onto the top of the under arm B when pressure is applied to it.

65 The arms B and D are preferably both of trapezoidal or similar shape with the adjacent surfaces flat or horizontal transversely so that the one can be pressed flat upon the other.

70 The suspended arm D is balanced by the weights W so that it may be readily and easily moved to and from the fixed arm B, and in normal position a space will remain between the two arms.

75 Above the movable arm D a swinging ram or rams F depend from levers F' which are connected by connecting rods J with a treadle G, the rams being capable of being swung into and out of the upward path of 80 the arm D. When the arm D is in normal position with a small space between it and the fixed arm B, the rams F will swing perpendicularly over the arm D and on depressing the treadle G the rams F are also 85 depressed and force the arm D down upon the arm B with an amount of pressure corresponding to that applied to the treadle.

85 As the space between the two arms will require adjustment for different thicknesses 90 of materials, the height to which the rams F rise is adjustable by regulating stop screws I against which the levers F' abut when in the raised position.

95 The rams F are hinged or pivoted and swing back into the position shown in broken lines in Fig. 1 clear of the arm D, to permit the arm D to be raised clear of the arm B when the operation of pressing is completed.

To the end of the suspended arm a small 100 metal plow or angular piece of metal H is attached which opens or spreads the seam as the leg or arm of the garment is drawn over the fixed arm B as shown in Fig. 3, the regulated space between the two arms maintaining the material in position until the pressure is applied.

105 The arms B and D may be heated by steam or gas pipes b and d.

110 For use on curved seams as for the sleeves of coats and jackets the arms B' and D' are curved as shown in Fig. 4. The top arm D',

- with which the rams F" co-act, is hung on the levers E' and the under arm B' is mounted on a round shaft, both arms being designed to revolve in order to use either the 5 longitudinal concave or convex surfaces to press the inside or outside seams of the sleeve. In all other respects, the arrangement does not differ from the one already described with reference to Figs. 1, 2 and 3.
- 10 Suitable means are provided for attaching the plow H' when in the reversed position.

In operation, the suspended arm D is lowered into normal position until the rams F swing perpendicularly over it and prevent 15 it rising and leaving the desired space between it and the arm B', the block C is removed from beneath the free end of the arm B' and the leg, sleeve or other part of the garment is drawn over the arm B and 20 the edges of the seam passed between the two arms, the plow H forcing open or apart the edges of the seam and laying them flat as shown in Fig. 3. When the material is in 25 position, the block C is replaced and the treadle G is depressed, bringing the arm D down upon the material with the desired amount of pressure to press the seam flat.

What I claim as my invention and desire to protect by Letters Patent is:—

- 30 1. In a garment-pressing machine, the combination of a frame; coöperating fixed and movable pressing arms mounted therein; ramming means located above the second-named arm and movable relatively to the 35 same into and out of position to contact therewith; and means acting to force said ramming means downward while in such contact, so as to press said second-named arm downward against the first-named arm.
- 40 2. In a garment-pressing machine, the combination of a frame; coöperating fixed and movable pressing arms mounted therein; ramming means located above and out of the path of movement of the second- 45 named arm and movable relatively to the same into such path; and means acting to force said ramming means downward after having moved into said path, so as to press the second-named arm downward against the 50 first-named arm.
- 55 3. In a garment-pressing machine, the combination of a frame; coöperating fixed and movable pressing arms mounted therein; a lever pivoted in said frame above the movable arm; a pivoted, depending ram carried by said lever to swing relatively to said movable arm into and out of position to engage the same; and actuating means for said lever operable to force said ram downward after having moved into engaging position and thereby press the movable arm 60 downward against the fixed arm.
- 65 4. In a garment-pressing machine, the combination of a frame; coöperating fixed and movable pressing arms mounted there-

in; a lever pivoted in said frame above the movable arm; a pivoted, depending ram carried by said lever to swing relatively to said movable arm into and out of position to engage the same; and a treadle connected to 70 rock said lever about its pivot and thereby force said ram downward after having moved into engaging position, so as to press the movable arm downward against the fixed arm.

5. In a garment-pressing machine, the combination of a frame; coöperating fixed and movable pressing arms mounted therein; a lever pivoted at its forward end in 80 said frame above the movable arm; a depending ram pivoted at its upper end to said lever intermediate the ends of the latter, said ram adapted to swing relatively to the movable arm into and out of position to engage the same; a pedal mounted in said frame; and a connecting rod pivoted at its lower end to said pedal and at its upper end to the rear end of said lever, to force said ram downward after having moved into 85 engaging position and thereby press the movable arm downward against the fixed arm.

6. In a garment-pressing machine, the combination of a frame; a pair of oppositely-arranged levers pivoted intermediate their ends in the upper portion of said frame; a movable pressing arm pivoted to the front ends of said levers; a counter-weight connected to the rear end of each lever; a fixed pressing arm mounted in said frame below said movable arm for coöperation therewith; and means movable into and out of position to engage the movable arm and operable to impose downward pressure directly upon the same when in engaging position, so as to press said movable arm 105 against said fixed arm.

7. In a garment-pressing machine, the combination of a frame; a pair of oppositely-arranged levers pivoted intermediate their ends in the upper portion of said frame; a movable pressing arm pivoted to the front ends of said levers; a counter-weight connected to the rear end of each lever; a fixed pressing arm mounted in said frame below said movable arm for coöperation therewith; ramming means movable relatively to said movable arm into and out of position to impose downward pressure directly thereon; and means operable to force said ramming means downward when 110 in engaging position, so as to press said movable arm against said fixed arm.

8. In a garment-pressing machine, the combination of a frame; a curved stationary pressing arm rotatably mounted therein; a 125 rotatably mounted curved pressing arm arranged above the stationary arm movable toward and from the same in coöperation therewith; and means initially movable transversely of and relatively to the mov- 130

able arm into position to engage the same, and subsequently movable downward to impose downward pressure directly upon said movable arm to force it against the stationary arm.

9. In a garment-pressing machine, the combination of a frame; coöperatitng stationary and movable pressing arms mounted therein; and means movable initially 10 transversely of and relatively to the movable arm into position to engage the same, and

subsequently movable downward to impose downward pressure directly upon said movable arm to force it against the stationary arm.

In testimony whereof I have hereunto set my hand in presence of two subscribing witnesses, this 10th day of February 1917.

WILLIAM WILKIE.
